UNITED STATES PATENT OFFICE.

HAMILTON L. MOULTON, OF PHILADELPHIA, PENNSYLVANIA.

DESIGN FOR A SIDE BAR OF RUB-ROLL FRAMES.

SPECIFICATION forming part of Design No. 16,794, dated July 13, 1886.

Application filed May 29, 1886. Serial No. 203,657. Term of patent 14 years.

To all whom it may concern:

Be it known that I, HAMILTON L. MOULTON, a citizen of the United States, residing at Philadelphia, Pennsylvania, have invented a new and original Design for the Rub-Roll Frame of a Carding-Machine, of which the following is a specification.

My design is shown in the accompanying drawing, which represents a side view of one of the frames.

The essential features of novelty in the design are the opposite side bars, A, of the frame, each of which has a lateral bend or offset, B, at or about the center, the offset being formed by a series of easy curves, as shown, although these curves may be sharper without departing from the main feature of the design.

The frame may have top, bottom, and cross bars, as shown by dotted lines; but these form no essential part of the design.

20

I claim—

The within-described design for the side bar of the rub-roll frame of a carding-machine, said design consisting of the bar having a lateral bend or offset at or about the center, all 25 substantially as shown and described.

In testimony whereof I have signed my name to this specification in the presence of two subscribing witnesses.

HAMILTON L. MOULTON.
